CLAIM

The ornamental design for a body brush, as shown and described.

DESCRIPTION

FIG. 1 is a front, top perspective view of a body brush showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of the rounded trapezoidal region on the rear of the body brush represents environmental structure and forms no part of the claimed design.
